(57) **CLAIM**

The ornamental design for portable yoga block speaker, as shown and described.

DESCRIPTION

FIG. 1 illustrates the perspective view of the portable yoga block speaker according to the present invention;
 FIG. 2 illustrates the exploded view of the portable yoga block speaker according to the present invention;
 FIG. 3 illustrates the partial exploded view of the portable yoga block speaker according to the present invention;
 FIG. 4 illustrates the front view of the portable yoga block speaker according to the present invention;
 FIG. 5 illustrates the rear view of the portable yoga block speaker according to the present invention;
 FIG. 6 illustrates the right view of the portable yoga block speaker according to the present invention;
 FIG. 7 illustrates the left view of the portable yoga block speaker according to the present invention;
 FIG. 8 illustrates the top view of the portable yoga block speaker according to the present invention; and,
 FIG. 9 illustrates the bottom view of the portable yoga block speaker according to the present invention.
